UNITED STATES PATENT OFFICE.

JAN COENRAAD JOHANKNEGT, OF THE HAGUE, NETHERLANDS.

ADVERTISING DEVICE.

Application filed July 23, 1924, Serial No. 727,817, and in the Netherlands May 10, 1924.

This invention relates to advertising devices.

The object of the invention is to provide a method of and apparatus for advertising.

5 According to the present invention advertising pictures or the like, either stationary or moving, are projected on a receiving surface mounted on board a boat, on which additionally the whole available space may 10 be utilized for the purposes of advertisements with or without artificial light.

This boat is adapted to be stationary or to cruise about at or between specially selected points such as bridges, ports, landing 15 stages and other large centres of traffic.

The invention further comprises various constructional arrangements applicable to the boat fitted up with the object hereinbefore mentioned.

20 One example of construction is illustrated diagrammatically with reference to the accompanying drawings, in which:

Figure 1 is a side view.

Figure 2 is a plan view.

25 Figure 3 a front view of a boat intended for advertising purposes according to the invention.

Figure 4 is a section on the line IV—IV of Fig. 3.

30 Figure 5 shows an arrangement for stopping or fixing the advertising screen.

Figure 6 is a diagrammatic section on an enlarged scale of the projecting cabin.

The boat consists of a hull 1 in the front 35 of which is mounted a screen 2 for projections whilst towards the middle there are provided the living cabins 3 and at the rear the projecting cabin 4.

It is desirable to arrange the screen 2 to 40 extend to a great height because then the pictures which are thrown thereon are more easily visible. The projecting apparatus must in this case, be arranged at an equal height. On the other hand it is desirable 45 to enable the upper members to be lowered when inoperative in order that the boat may easily pass beneath low bridges and also in order not to detract from the monuments of the towns. This object is realized in the 50 form of construction illustrated in the following manner:

The screen for receiving the projections is carried by two uprights 10 which are movable on a shaft 9 and to the base of which 55 are fixed toothed sectors 11 with which pinions 12 mesh. The two pinions 12 are

mounted on a common shaft 120 which, by means of toothed wheels and a worm or like wheel are given a rotary movement by means of a worm 13 to which is keyed a 60 hand wheel 14. When the screen has reached its topmost position a pawl 16 shown in Fig. 5 engages in the teeth of a stop plate 15 mounted on the upper part of the worm 13. The pawl 16 is operated against the action 65 of a spring 160 by means of a traction rod 17 which is pivoted to the end of a bracket 18 mounted on the shaft 9. The axis of the worm may however, be stopped in any suitable manner.

The exhibition screen preferably consists of a dulled or ground glass mirror 19, the dulled surface of which is turned to the front where it is protected for some distance by a sheet of glass 20 to prevent the dulled face 70 from becoming moist. It is however, possible to throw pictures on to a prepared or unprepared canvas or on to a simply dulled sheet of glass, the dulled face of which is coated with a transparent material impermeable to water such as for instance, paraffin. The side walls of the uprights of the projecting screen are occupied by advertising panels 75 21 which are preferably placed obliquely towards the front whilst above the screen an automatic time indicator 22 is arranged. A frame is provided all round the screen which frame may be utilized for advertising purposes and/or ornamenting the whole. In the raised position the screen may be held by 80 cables fixed to the hull, which are not shown.

Beneath the screen between the uprights 10 is arranged an advertising panel 23 pivotal about a horizontal axis 24. The object of this is to enable the advertising panel 23 95 to be turned when the screen is lowered so that then the rear face of the panel comes to the top and the front face is protected from any deterioration.

The rotation of this advertising panel 23 100 may, if necessary, be effected by hand after which the advertising panel is maintained in any desired position. The rotation may however also be obtained by fixing on the shafts 24 small toothed wheels connected by 105 chains with toothed wheels of twice the diameter mounted on the shafts 9 or their bearings so that when the screen is turned the advertising panel describes a rotary movement twice the extent. It is, however, 110 also possible to utilize for advertisements both faces of the advertising panel 23 and

to cause the latter to rotate about an axis during projection of the advertising matter so that the two faces are successively presented to the front.

5 If necessary, the living cabins may be rendered accessible from the front by means of a tunnel 260 which facilitates access beneath the advertising panel 23.

In plan view the cabins 3 have the form of 10 a trapezium, the side walls above the deck being utilized for placing fixed advertising panels 27 and 28 connected for example by hinges. The panels 28 may be folded down against the panels 27 so that the panels 15 mutually protect one another.

The cabin 4 is formed as shown by three telescopic elements 29, 30 and 31 the lower element 29 of which is fixed to the hull or body of the ship and is partially prolonged 20 above the deck. The desired displacement of the cabin 31 upwards and downwards is obtained by an extensible member such as a "lazy tongs" device the two fixed points 35 and 37 of which are respectively connected 25 to the hull 1 of the boat and to the cabin 31 whilst the two movable points 36 and 38 may slide along slide pieces 32 and 33 the first of these latter being connected with the hull 1 and the second with the cabin 31. 30 The points 38 may for example be displaced by means of helicoidal screws having an automatic brake whilst the helicoidal screws may in their turn be actuated by means of screw wheels, pawls or like members. All 35 these parts are well known and are therefore not shown. Between the elements 29, 30 and 31 there are rollers 39 which facilitate the telescopic movement whilst the element 30 is raised by the element 31 by means 40 of abutments 300 and is itself arrested in a raised position by the element 29 by means of abutments 290.

To give access to the cabin 31 one of the four sides is free, preferably the front face 45 which is turned towards the projection screen. One of the other sides may also be utilized for the same object. A door 42 opening towards the exterior is provided in the element 29, a sliding door 43 in the element 30 and a door 44 opening inwardly in the cabin 31.

In the lower position of the elements these three doors coincide so that from the deck 55 one can pass directly into the cabin where the latter can be raised by means of the device 34. When the cabin is in the highest position it may be reached by means of a ladder 40 the parts of which are fixed to the elements 29, 30 and 31 and also by the intermediary of a second door 41 which is arranged in the same wall of the cabin 31. This second door may however be dispensed with.

60 The cabin is closed by a roof 46 which overlaps it sufficiently so that in the position

when the elements are telescoped one in the other no water can penetrate therein. Finally in the cabin there is a projecting apparatus 45 by means of which the desired pictures may be thrown on to the screen 2. 70 The walls of the elements 29, 30 and 31 which are not utilized for the cabin and the doors are occupied by advertising panels. In the walls of the cabin openings 310 for light and air may be provided. In the 75 raised position the cabin may be supported on the hull by means of cables which are not shown in the drawings.

As the weight of the screen is considerable the lowering and raising of the same causes 80 a considerable displacement of the centre of gravity. Ballast tanks 5 and 6 are therefore provided at the front and rear of the boat 1 which tanks are in adjustable communication with one another and with the outside by means of a pipe 7 and a pump 8. The pump 8 may also be utilized as a bilge pump for the other spaces.

Dependent on the raised or lowered position of the screen its weight acts on the bow 90 and the centre of the boat respectively. In both cases the horizontal position of the boat may be maintained by causing an exactly predetermined quantity of water to pass from one tank into the other. The boat 95 may be caused to be more deeply immersed by introducing more water into both tanks. This may be of advantage for passing under low bridges.

The surface available for advertising may 100 be also suitably increased by providing the parts located above the deck such for example as the screen, the projection cabin and the dwelling cabins or some of them with an arrangement for supporting a canvas which 105 may be utilized for advertisements.

If desired an arrangement for causing 110 publicity by acoustic means in order to attract attention to the advertisement shown, and for conveying information of any suitable kind and the like may be provided on the boat. An arrangement of this kind may, for instance, be formed by a loud speaker, a megaphone or a device of this type.

When the screen is lowered its advertising 115 surface is covered in an impermeable manner. The screen then rests on the roof of the cabins 3.

Various other forms of construction come 120 within the scope of the invention. The displacement of the screen may for instance be effected by means of a winch and a steel cable on each upright. Further the screen for the advertisements may be made movable between the uprights with the object of being able to bring it nearer to the axis of rotation during the rotary movement of raising and lowering it and thus to diminish the momentum.

Finally the whole screen may be caused to 125

descend vertically into the boat whilst a combination would also permit of rendering the frame of the screen telescopic and at the same time to enable it to be turned about a 5 horizontal axis.

The cabin may also be constructed in various ways. It may for instance be raised by means of one or more winches, with steel cable or one or more screw cranes. The 10 whole may also be constructed of three cylinders, the two outer ones of which are provided on their inner faces with three or a larger number of helical guides in which the two inner cylinders arranged inside are displaced on rollers so that the latter can be 15 raised by means of small winches with steel cables.

Finally the cabin may be suspended to one or more masts or the cabin may be arranged 20 on uprights raised on hinges which may be caused to rise or fall by means of winches or toothed sectors. Between these uprights lad-

der posts may be fixed. It is finally also possible to keep the projection cabin in the lowered position and to throw the pictures 25 on to the elevated screen by means of a periscope which is partially or entirely removable.

What I claim is:

A boat arranged for advertising purposes 30 including a receiving screen, a projecting apparatus for projecting advertising pictures either stationary or moving onto said screen, a telescopic cabin containing said projecting apparatus, means for raising said cabin high 35 above the deck or lowering same into the body of the ship and means for movably mounting said receiving screen opposite said cabin comprising a supporting structure capable of being lowered onto the deck of 40 the boat.

In testimony whereof I have hereunto set my hand.

JAN COENRAAD JOHANKNEGT.
